UNITED STATES PATENT OFFICE

RUSSELL T. KINGSFORD, OF WYNCOTE, PENNSYLVANIA, ASSIGNOR TO ATWATER KENT MANUFACTURING COMPANY, OF PHILADELPHIA, PENNSYLVANIA, A CORPORATION OF PENNSYLVANIA

RADIOSPEAKER

Application filed December 16, 1926. Serial No. 155,159.

My invention relates to telephonic apparatus, and particularly to amplifying telephones, loud speakers or radio speakers, utilized in connection with radio receiving apparatus.

In accordance with my invention, the air-vibrating diaphragm or tympanum is shielded or protected by a housing structure conforming generally in configuration with that of the diaphragm, and more particularly, the aforesaid diaphragm is conical and of relatively large area and is disposed within a generally conical housing, whereby, should the instrument be overturned, the diaphragm is protected from injury.

Further in accordance with my invention, the air-vibrating diaphragm or tympanum of paper, metal, or other suitable material, preferably of large area or diameter and preferably conical, has its peripheral edge spaced from a protecting ring-like housing and is supported solely by a member substantially non-flexible in a direction coinciding with the gravitational plane of the diaphragm and of relatively great flexibility in a plane substantially at right angles to said gravitational plane.

My invention resides in the apparatus and features of construction of the character hereinafter described and claimed.

For an understanding of some of the forms my invention may take, reference is to be had to the accompanying drawings in which:

Figure 1 is a vertical sectional view of apparatus constructed in accordance with my invention.

Figs. 2 and 3 are, respectively, rear and front views of the structure shown in Fig. 1.

Fig. 4 is a horizontal sectional view of the apparatus shown in Fig. 1.

Fig. 5 is an enlarged vertical sectional view of a part of the apparatus shown in Fig. 1.

Fig. 6 is a horizontal sectional view taken on the line 6—6 of Fig. 1 looking in the direction of the arrows.

Referring to the drawings, 1 is a stand or supporting member to which is suitably secured, as by bolt 2, the base 3 of a conical housing structure comprising the ring or annulus 4 from which inwardly and at an angle

from the plane thereof extend the ribs 5 terminating in the shell or casing 6.

Secured within the casing 6 is a telephone magnet system M of any suitable character, but preferably of the type disclosed in my co-pending application, Serial No. 155,158, filed Dec. 16, 1926, and, therefore, comprising the spaced magnet frames or yokes 7, 7 between which are disposed the inwardly extending pole pieces 8, screws 9 or equivalent fastening elements serving to unite frames 7, 7 and pole pieces 8 and secure the combined structure to casing 6.

When the casing 6 is of magnetic material, screws 9 should be non-magnetic in character, as brass or the like. In the event that casing 6 is of non-magnetic material, screws 9 may be either magnetic or non-magnetic, as found desirable.

Fixed between the frames 7, 7 by the bolt 10 is one end of the armature bar or reed 11 whose free end is received in the air gap between the aforesaid pole pieces 8 and maintained in adjusted position with respect thereto by adjusting screws 12 threaded through the frames 7, 7 and co-acting with opposite faces of the reed 11. Disposed between the frames 7, 7 for holding them in suitable spaced relation, at the end thereof opposite the bolt 10 is a spacing washer or element 13 through which and the plates 7, 7 passes a bolt 14, while adjacent the bolt 10 on each side of the reed 11 are spacing washers, not shown, the combined thickness of which and the reed 11 is substantially the same as that of spacing washer 13 and also of the pole pieces 8.

The magnet system M may be utilized to actuate any shape and type of air-vibrating or diaphragm structure D, of paper, metal or other suitable material. Preferably, however, diaphragm D is conical and of relatively large area, as six inches or more in diameter or its equivalent, and one which for both axial and transverse vibration is unrestricted throughout and which is entirely free to vibrate at its extreme periphery at the frequency and with the amplitude of vibrations transmitted therethrough from its apex or center.

As shown, particularly in Figs. 1, 4 and 5, 100

diaphragm D, at a suitable distance from its edge has imparted thereto a stiffening bend 15 and one or both sides of its extreme peripheral edge may have a layer 16 of felt or similar fabric applied thereto.

5 For the reception of the peripheral edge of the diaphragm D, the ring or annulus 4 preferably is circumferentially grooved as indicated at 17, Figs. 1, 4 and 5.

10 Spaced from the ring 4 and its groove 17 to form a housing for said peripheral edge of the diaphragm is the second ring or annulus 18 suitably secured to the ring 4, preferably by utilizing spacing washers or elements 19 15 in conjunction with screws 20.

15 The diaphragm D at its apex may be provided with the inner and outer conical facing washers 21 and 22, the latter forming a seat for the angular arms of the thereto-secured 20 bracket 23 terminating in a pocket for the reception of the end of a member 24 extending laterally of the vibratory armature or reed 11 and secured in the aforesaid pocket by a bolt 25 or similar fastening element.

25 It will be understood that while I have shown the diaphragm made in the form of a symmetrical circular cone, other types of cones may sometimes be used to advantage, such as oval, eccentric or pyramidal, and I do 20 not limit myself to any one type.

As illustrated in my aforesaid application, the reed or armature bar 11 is disposed in a plane extending substantially at right angles to the gravitational plane of the diaphragm.

25 Inasmuch as the armature bar is mounted for pivotal or oscillatory movement, a to-and-fro movement is imparted to the end of member 24 in the longitudinal plane of said armature bar. Should the member 24 be non-flexible,

40 such, for example, as is constituted by the rigid pin or bar of the prior art, the diaphragm would be given a transverse bodily to-and-fro movement with resultant distorted or imperfect sound reproduction, to eliminate which member 24 should be so constructed

45 as to be flexible in the plane wherein occurs the aforesaid to-and-fro movement, whereby, due to its inertia, the diaphragm D partakes but slightly, if at all, of the to-and-fro movement of the end of the thereto connected supporting member 24. At the same time, member 24 should be so constructed as to be substantially non-flexible in the direction of the gravitational plane of the dia-

50 phragm D whereby the same may be supported without flexing or bending said member 24. In accordance with this phase of my invention, the member 22 may be of substantially greater breadth than thickness and so disposed with respect to the diaphragm D 55 that the weight is carried in the direction of breadth rather than width.

Diaphragms forming a part of the loud 60 speakers of the prior art are usually constructed of paper, or similar material easily

fractured should the instrument overturn.

By my invention, however, the danger of such mischance is to a substantial degree eliminated due to the fact that the ring 4, 70 ribs 5 and casing 6 form a housing of generally conical shape for the diaphragm D. Thus, should the instrument as viewed in Fig. 1 fall toward the right, some part of the structure just mentioned would take the shock and ordinarily prevent damage to the 75 diaphragm. Or, should the instrument fall toward the left, the ring 18 would intervene, and if subjected to an end-on fall one or both of the rings 4 and 18 would absorb the impact. The casing 6, besides functioning to thus prevent damage to the diaphragm, also 80 functions as an enclosure for the magnetic system M.

The housing structure comprising the ring 4, 85 ribs 5 and casing 6, as well as the ring 18, may be constructed of such material as may be found desirable. Ordinarily, such structures should be cast iron castings or preferably die castings.

The ring 4 or the lowermost rib 5, preferably the latter, may be provided with a perforation 26 through which passes a cable 27 including the conductors leading to the coil associated with the magnetic system and traversed by the sound-representing current.

90 It may also be desirable to provide an opening 28 in the casing 6 through which may be passed a tool for adjusting one of the screws 12 after the apparatus is assembled. By so doing, the air gap between the pole 100 piece extensions of the pole pieces 8 and the free end of reed 11 may be adjusted to suit the characteristics of the particular apparatus with which the herein disclosed device 105 is to be used.

What I claim is:

1. The combination with a conical diaphragm of large area and having a freely 110 vibrating periphery, of substantially non-flexible structure overlying the convex side of said diaphragm and comprising a member conforming with and closely spaced from its peripheral edge.

2. The combination with a conical diaphragm of large area, of a magnet system 115 disposed adjacent the apex of said diaphragm, and a casing within which said magnet system is disposed presenting an open wall of area less than the base area of said conical diaphragm to the convex side thereof.

120 3. The combination with a conical diaphragm of large area and having a freely vibrating periphery, of a magnet system disposed adjacent the apex of said diaphragm, 125 and a housing structure comprising a ring-shaped circumferentially-grooved member spaced from the periphery of said diaphragm, ribs extending toward the center of said member and overlying the convex side of 130

said diaphragm and a casing within which said magnet system is confined.

4. The combination with a conical diaphragm of large area and having a freely vibrating periphery, of a magnet system disposed adjacent the apex of said diaphragm, a housing structure comprising a ring-shaped member spaced from the periphery of said diaphragm, ribs extending toward the center of said member and overlying the convex side of said diaphragm and a casing within which said magnet system is disposed, and a second ring-shaped member secured in spaced relation to said first-named ring-shaped member.

5. The combination with a loud speaking telephone including a magnet system comprising a vibratile member, a conical diaphragm of large area and having a freely vibrating periphery, and means for securing said diaphragm solely adjacent its apex to said vibratile member comprising a member having substantially greater flexibility in one direction than in another, of a housing structure comprising a ring-shaped member spaced from the periphery of said diaphragm, ribs extending toward the center of said ring-shaped member and overlying the convex side of said diaphragm, and a casing within which said magnet system is confined.

6. The combination with a loud speaking telephone including a magnet system comprising a vibratile member, a conical diaphragm of large area and having a freely vibrating periphery, and means for securing said diaphragm solely adjacent its apex to said vibratile member comprising a member having substantially greater flexibility in one direction than in another, of a housing structure comprising a ring-shaped member spaced from the periphery of said diaphragm, ribs extending toward the center of said ring-shaped member out of the plane thereof and overlying the convex side of said diaphragm, and a casing within which said magnet system is confined.

7. The combination with a loud speaking telephone including a magnet system comprising a vibratile member, a conical diaphragm of large area and having a freely vibrating periphery, and means for securing said diaphragm solely adjacent its center to said vibratile member comprising a member having substantially greater flexibility in one direction than in another, of a housing structure comprising a ring-shaped member spaced from the periphery of said diaphragm, ribs extending toward the center of said member and overlying the convex side of said diaphragm and a casing within which said magnet system is confined, and a second ring-shaped member secured in spaced relation to said first-named ring-shaped member and between which the periphery of said diaphragm is freely vibratory.

8. The combination with a conical diaphragm of large area and having a freely vibrating periphery, and a vibration-transmitting member secured to said diaphragm adjacent the apex thereof and comprising the sole support therefor, of a housing structure comprising annular members disposed on opposite sides of said diaphragm and closely spaced therefrom adjacent the periphery thereof.

9. The combination with a conical diaphragm of large area having a stiffening flange terminating in the freely vibrating periphery of said diaphragm, and a vibration-transmitting member secured to said diaphragm adjacent the apex thereof and comprising the sole support therefor, of a housing structure comprising annular members disposed on opposite sides of and extending adjacent said flange.

10. The combination with a conical diaphragm of large area and having a freely vibrating periphery, of a casing on the convex side of said diaphragm, a magnet system disposed within said casing and comprising a vibration-transmitting member extending freely through said conical diaphragm substantially at the apex thereof, and structure secured to and extending inwardly from said diaphragm, attached to said member.

11. The combination with a conical diaphragm of large area, of a magnet system disposed adjacent the apex of said diaphragm, and housing structure for said diaphragm and magnet system comprising a ring-shaped member in a plane parallel to and adjacent the base of said conical diaphragm, rib structure extending from said member overlying and substantially conforming to the convex side of said conical diaphragm, and a casing enclosing said magnet system extending outwardly from the apex of the diaphragm and said rib structure.
